[57] CLAIM

The ornamental design for a free standing tape drive cabinet, as shown and described.

DESCRIPTION

FIG. 1 is a top, front, left side perspective view of the free standing tape drive cabinet showing our new design, the stand being shown in broken lines for illustrative purposes only;

FIG. 2 is a front elevational view thereof on an enlarged scale;

FIG. 3 is a right side elevational view thereof on an enlarged scale;

FIG. 4 is a left side elevational thereof on an enlarged scale;

FIG. 5 is a top plan view thereof on an enlarged scale;

FIG. 6 is a rear elevational view thereof on an enlarged scale; and

FIG. 7 is a bottom plan view thereof on an enlarged scale.
